UNITED STATES PATENT OFFICE.

GEORGE A. AYER, OF EASTHAMPTON, MASSACHUSETTS, ASSIGNOR TO WEST BOYLSTON MANUFACTURING CO., OF EASTHAMPTON, MASSACHUSETTS, A CORPORATION OF MASSACHUSETTS.

CLOTH-TESTING MACHINE.

1,231,231.

Specification of Letters Patent. Patented June 26, 1917.

Application filed January 6, 1915. Serial No. 749.

To all whom it may concern:

Be it known that I, GEORGE A. AYER, a citizen of the United States, residing at Easthampton, county of Hampshire, State 5 of Massachusetts, have invented an Improvement in Cloth-Testing Machines, of which the following description, in connection with the accompanying drawing, is a specification, like characters on the drawing representing like parts.

This invention relates to cloth testing machines. These machines are constructed to furnish means for ascertaining one of the qualities of cloth—its tensile strength.

15 It is customary to provide such machines with jaws which are clamped together by means of thumb screws. The operation of these gripping means, due to their structural location, is more or less awkward and represents a relatively large portion of the time factor involved in conducting such a test.

The object of this improved cloth testing machine is to provide adjustable clamping jaws which are readily and easily operated.

25 Another object is to secure jaws which are powerful in their gripping force and function positively and quickly.

Other objects of the invention will more fully appear from the following description 30 and the accompanying drawings and will be pointed out in the annexed claims.

In this novel construction, the jaws are pivoted adjacent their lower ends and a slide is interposed between the two jaws. This 35 slide operatively engages the lever of said jaws preferably having a wedge-shaped portion at its upper end merging into an outwardly turned cam surface which effectuates the forcible separation of the upper parts of

40 the pivoted jaws and results, due to the great leverage obtained, in the powerful gripping quality of the clamping portion of the jaws. This cam-surface bearing slide is actuated by means of a handle conveniently located adjacent the jaws.

45 The handle is adapted to rotate a small pinion which engages teeth carried by this slide and positive movement of the slide is thereby attained. The handle is so constructed

50 that when the jaws are in operative position, the handle is retained out of the way. And, to allow for necessary adjustment for different thicknesses of cloth, the handle is provided with a toothed plunger which is 55 adapted selectively to engage different teeth

of a small toothed wheel rotatable with the small slide-operating pinion.

There has been illustrated in the accompanying drawings a selected embodiment of the improved cloth testing machine which 60 will now be described.

Figure 1 is a front elevation of the cloth testing machine;

Fig. 2 is a side elevation of one of the clamping members;

Fig. 3 is a front elevation, partially broken away, of a clamping member—the handle being shown in a different position from that in Fig. 2;

Fig. 4 is a sectional detail showing the 70 rack and pinion;

Fig. 5 is a sectional view on the line 5—5, Fig. 4.

The cloth testing machine, in this preferred construction, consists of a standard 75 1, with a suitable base 2. Midway the standard is affixed the gear 3 actuated through a worm or other suitable gear, not shown, by the driven pulley 4. The cloth

5, the tensile strength of which is to be 80 tested, is secured between the upper and lower clamping members 6 and 7, respectively.

The member 6 is pivotally affixed to the scale beam 8 which is balanced at 9, its fulcrum arm being attached to the ten- 85 sion indicating means, comprising a dial 10 and its hand 11.

The indicating means together with the scale beam 8 is borne by the upper portion of the standard 1. The mem- 90 ber 7 is adjustably secured to the socket 12 by means of the set screw 13, while the socket 12, is in turn, preferably formed in the slide 14 which is adapted to be recipro- 95 cated in the runway formed by the twin flanged strips 15 and 16 attached to the standard 1.

The slide 14 is reciprocated by means of the rod 17, the lower end of which is pivotally connected to the slide and re- 100 tained by means of a suitable washer nut 18.

The upper end of the rod 17 is connected to 105 the gear 3 by means of a stud 19 secured to the face of the gear 3. The gear 3 is adapt- ed to be actuated counter-clockwise when a piece of cloth 5 is being tested and the re- 110 sultant motion of the slide 14 is in a verti- cally downward direction.

The upper and lower clamping members are similar and consist, as shown in Figs. 2, 3 and 4, of the opposed jaws 21 and 22, piv- 115 otally secured together at 23. The relatively

fixed jaw 21 at its upper end is bifurcated and is adapted to have pivotally secured between its ears a link 24 by which means it is affixed to the scale beam 8. The lower end 5 of the jaw 21 terminates in an irregularly toothed portion 25. The movable jaw 22 has, at its lower end, a similar and opposed toothed portion 26, pivoted at 27, and is adapted, in combination with the toothed portion 25 of the other jaw 21, firmly to grip a piece of cloth.

The actuation of the clamping members is simple and their gripping function is readily and positively accomplished by 15 means of the handle 28 rotatably affixed on a stud 29 which is journaled in the jaw 21. The handle is centrally bored and adapted to receive therethrough a rod 30 carrying at its inner end a plunger 31, reciprocal in 20 the enlarged boring 32 of the handle. The plunger is normally held in engagement, by the coiled spring 20, with the teeth 33 of a wheel 34 which is secured to the stud 29 by a key 35. The stud 29 also carries rotatable 25 therewith a pinion 36 keyed thereto at 37. This pinion vertically reciprocates a rack 38 which is slidably mounted in a runway 39 formed in the fixed jaw 21 and which is thus secured therein by the flanges 41 which 30 are, in turn, affixed to the jaw by means of suitable screws 42. The upper end of this rack terminates in a wedge-shaped element 43 having on its under side a cam surface 44 which, as the rack descends, causes the 35 upper end 45 of the movable jaw 22 to ride out its face and thus to rock the jaw 22 about the pivot 23. This outward movement of the end 45 effectuates the opposite and inward motion of the toothed portion 40 26 forcing the opposed jaw portions together. The leverage attained by exerting the outward pressure upon the long arm of the lever fulcrum at 23 is very great and effects the retentive holding of a piece of 45 fabric inserted in the jaws. The fabric being thus held, the pulley 4 is actuated, the gear 3 slowly revolved causing the rod 17 to push downwardly the slide 14, whence the lower clamping member is pulled away 50 from the upper and the tension upon the cloth therebetween is indicated by the dial.

It is to be understood that the construction disclosed herein is illustrative but not restrictive and that the same may be modified within the meaning and scope of the 55 claims which follow.

Having fully described my invention, what I claim as new and desire to secure by Letters Patent is:

60 1. In a cloth testing machine, a clamping member comprising a fixed and a relatively movable jaw, means for closing said jaws including a rack slidably mounted upon the fixed jaw and having means operable to engage the movable jaw, a pinion engaging

said rack and having a rigidly attached shaft mounted in bearings on said fixed jaw, a handle rotatably mounted on said shaft, a peripherally recessed member keyed on said shaft, and a spring-pressed plunger 70 carried by said handle adapted to engage selectively said recesses.

2. In a cloth testing machine, a clamping member comprising gripping jaws, means for actuating said jaws including a rack and 75 a pinion having a rigidly attached shaft mounted in one of said jaws, a handle rotatably mounted upon said shaft and means carried by said handle adapted operatively but detachably to engage said shaft. 80

3. In a cloth testing machine, a clamping member comprising a fixed and a relatively movable jaw, means for closing said jaws including a rack slidably mounted upon the fixed jaw and having means operable to engage the movable jaw, a pinion engaging said rack and having a rigidly attached shaft mounted in bearings on said fixed jaw, a handle rotatably mounted upon said shaft and means carried by said handle adapted 90 operatively but detachably to engage said shaft. 85

4. In a device of the class described, a clamping member comprising a fixed and a relatively movable jaw, means for closing 95 said jaws including a rack slidably mounted upon the fixed jaw and having a cam engaging the movable jaw, a pinion engaging said rack and having a rigidly attached shaft mounted in bearings on said fixed jaw, a handle rotatably mounted upon said shaft and means carried by said handle adapted 100 operatively but detachably to engage said shaft. 100

5. In a cloth testing machine, a clamping member, comprising a fixed jaw and a movable jaw, said jaws having opposed gripping means at one end, said movable jaw being pivotally secured to said fixed jaw, a rack slidably mounted upon said fixed 110 jaw adjacent said movable jaw, means operable by said rack to actuate the latter and a pinion carried by said fixed jaw adapted to reciprocate said rack whereby said movable jaw may be actuated about the pivot 115 and the gripping means retentively closed.

6. In a cloth testing machine, a clamping member, comprising a fixed jaw and a movable jaw pivotally secured to the fixed jaw, said jaws having opposed gripping means 120 at one end, a rack adapted to reciprocate between said jaws, a pinion adapted to actuate said rack, means for manually actuating said pinion, a cam surface on the rack adapted to engage the upper face of 125 said movable jaw whereby said jaw may be actuated and the gripping means retentively closed.

7. In a cloth testing machine, a cloth-gripping means, the members thereof hav- 130

ing pivoted clamping relation, an instrumentality slidably mounted between said members and movable to close the same into clamping position, and means rotatable to 5 move said instrumentality.

In testimony whereof, I have signed my

name to this specification, in the presence of two subscribing witnesses.

GEORGE A. AYER.
